RACK FOR SUPPORTING A THERAPEUTIC COMPRESS IN A LIQUID BATH

Lee Jensen, Chattanooga, Tenn.

Application May 26, 1952, Serial No. 19,900

Term of patent 14 years

(Cl. D80—9)

To all whom it may concern:

Be it known that I, Lee Jensen, a citizen of the United States of America, residing at Chattanooga, in the county of Hamilton and State of Tennessee, have invented a new, original, and ornamental Design for a Rack for Supporting a Therapeutic Compress in a Liquid Bath, of which the following is a specification, reference being had to the accompanying drawing, forming part thereof.

Figure 1 is a perspective view of a rack for supporting a therapeutic compress in a liquid bath showing my new design.

Figure 2 is a side view in elevation of the rack, and

Figure 3 is an end view of the rack.

I claim:

The ornamental design for a rack for supporting a therapeutic compress in a liquid bath, as shown.

LEE JENSEN.
